UNITED STATES PATENT OFFICE.

ANDREW M. CHEESEMAN, OF BELLWOOD, PENNSYLVANIA.

ROOFING-TILE.

SPECIFICATION forming part of Letters Patent No. 511,507, dated December 26, 1893.

Application filed June 10, 1893. Serial No. 477,159. (No model.)

To all whom it may concern:

Be it known that I, ANDREW M. CHEESEMAN, of Bellwood, in the county of Blair and State of Pennsylvania, have invented a new and useful Improvement in Roofing-Tiles, of which the following is a full, clear, and exact description, reference being had to the accompanying drawings, forming part of this specification, in which—

10 Figure 1 is a top plan view of a series of tiles constructed in accordance with my invention. Fig. 2 is a longitudinal section on the line II—II of Fig. 1. Fig. 3 is a cross-section on the line III—III of Fig. 1. Fig. 4 is 15 a bottom plan view; and Fig. 5 is a detail view hereinafter referred to.

In the drawings, 2, 2, represent the tiles, which are of substantially rectangular shape, and are provided along one margin with a 20 semi-cylindrical or angular overlap or wing 3, having at its upper end a reduced portion 4 joined thereto by a connecting shoulder 5. The opposite edge of the tile is provided with a continuous projecting flange 6, which, near 25 its lower end, is provided with a shoulder 7, below which the edge of the tile is cut away to bring the flange within the corresponding flange of the next tile below. This shoulder is perforated for the insertion of a nail or 30 screw, and against it abuts the end of the flange below. Inside the flange is an inclined ridge 8, which begins near the top of the tile at the level of the shoulder 5 and tapers thence 35 downwardly, being preferably flush with the bottom edge of the tile. Above the ridge or ledge 8 the body of the tile is beveled downwardly to give a close adjustment of the next tile, and in this beveled portion are the nail or screw holes 9 for securing it to the roof. On 40 the under side of the tile and extending from these holes to its edge are grooves 10. On the under side of each tile is a cross rib 11, preferably of the same thickness as the tile, and from this rib extend the reticulated ribs 45 12, which taper upwardly and at the top are flush with the tile-body. These ribs rest upon the roof-structure, giving the tile strength and stiffness, as well as aiding in the prevention of warping while the tile is fired, and 50 may be perforated, if desired, to allow a circulation of air below the tile. The tiles are set in position on the roof side by side, the wing of each tile fitting over the flange of

the next and resting upon the ridge or ledge within this flange. When the next course is 55 laid, the wings at their lower parts fit over the reduced portions 4 and abut against the shoulders 5 and the ends of the ridges 8, while the flange of the first row incloses the narrowed portion of the next above and abuts 60 against the shoulders 7.

Whenever one of the tiles becomes broken it is removed and a tile is provided with the attachment of Fig. 5. This consists of a pin 13 arranged to enter the nail-hole and having 65 a strip extending therefrom through the groove 10 and carrying at its outer end a rearwardly projecting leaf-spring 14, having a bent upper portion 15 forming a clamp which, when the tile is pushed into place, takes about 70 the lowest rib 11 of the next tile above, the leaf-spring forcing it up into place. The groove thus affords a convenient means for replacing broken tiles by the use of this spring attachment. 75

The advantages of the tile result from the shoulder upon the marginal flange in connection with the narrowing of the lower end of the tile without cutting away the flange.

Within the scope of my invention as defined 80 in the claims, I may make various modifications in the form and construction of the parts, although those I have shown I deem best suited for the purpose.

I claim—

1. A tile of substantially rectangular form, having a marginal wing along one edge, said wing having a reduced portion at its upper end, a cut-away portion at the opposite lower corner of the tile, and a continuous flange 90 along this opposite edge having a perforated shoulder at the cut-away portion; substantially as described. 85

2. A tile having nail holes and grooves extending on its under side from the holes to 95 its edge, substantially as described.

3. A tile having a transverse rib on its under side, and a series of diagonal tapering ribs extending upwardly therefrom and crossing each other; substantially as described. 100

In testimony whereof I have hereunto set my hand.

ANDREW M. CHEESEMAN.
